UNITED STATES PATENT OFFICE.

JOSEPH BOLLINGER, OF BRACKEN, INDIANA.

COMBINED CORN PLANTER AND PLOW.

SPECIFICATION forming part of Letters Patent No. 313,296, dated March 3, 1885.

Application filed October 22, 1884. (No model.)

To all whom it may concern:

Be it known that I, JOSEPH BOLLINGER, a citizen of the United States, residing at Bracken, in the county of Huntington and State of Indiana, have invented certain new and useful Improvements in Combined Corn Planter and Plow; and I do hereby declare that the following is a full, clear, and exact description of the same, reference being had to the annexed drawings, making a part of this specification, and to the letters and figures of reference marked thereon.

Figure 1 of the drawings is a perspective view of my invention, and Fig. 2 a longitudinal section thereof.

The object of the present invention is to provide a combined corn-planter and corn-plow that will successfully plant the corn without in any manner having first scored, furrowed out, or marked the ground to be planted.

The invention consists in the several details of construction, substantially as shown in the drawings, and hereinafter described and claimed.

In the accompanying drawings, A represents the side bars, and B the axle rigidly connected thereto, upon the ends of which are mounted suitable driving-wheels, C, a tongue, D, being connected to the axle and extending forward sufficiently to attach the team thereto. The seed-boxes E are supported above the axle B by metal braces F, connected thereto and to the boxes, a seat, a, being provided between the boxes for the driver, and also a foot-rest, b, attached to the tongue D.

To the forward end of the side bars, A, is pivoted a transverse bar, G, provided near its ends with inwardly-extending arms e, to which are connected at an acute angle the standards d, carrying suitable shovels, H.

The beam G being pivoted as hereinbefore described the shovels H may be raised or lowered at will by means of the lever I, which is pivoted at its lower end to the tongue D. This lever is also pivoted to a longitudinal rod, J, which has its ends pivoted to brackets e, upon the transverse pivoted bar G, and a similar bar, K, pivoted to the rear ends of the side bars, A, which also has arms f and standards g, the latter having attached bifurcated shovels or coverers L.

The boxes E, which contain the grain or

seed, are provided at their bottom with discharge-openings h, under which is arranged a transverse feed-slide, M, having openings i, 55 corresponding in size and shape to the openings in the feed-boxes, said slide having a lever, N, by which means the slide can be held stationary, so that no corn will be dropped while turning or moving the machine about 60 when not in use. The slide M is operated by means of cam-blocks k, working in contact with the inclined end l of the slide, a spring, m, bearing against the opposite end of the slide, forcing it back to its former position after being 65 acted upon by the cam-blocks. The slide M, immediately under the opening therein, has rigidly secured to it the upper ends of rubber or other flexible tubes, P, the opposite or lower ends of said tubes being secured to the standards d in the rear of the shovels H. To facilitate their attachment at this point, the standards are preferably grooved to form seats for the ends of the tubes, the same moving with the slide and also with the shovels when raised 70 or lowered, the latter being set far enough apart in the construction of the machine to make room between them equal to the distance required by the farmer between two rows of corn.

As the machine is drawn across the field and the furrows are being made by the shovels H, and the slide M operated by the cam-blocks k, on one of the wheels C, the corn drops from the boxes E, through the openings h i, 85 down through the tubes P into the furrows behind the shovels, and is covered by the bifurcated shovels L as the machine moves along.

The lever I is brought in use when it is desired to elevate the shovels H L, and after the 90 first row is made, a guide, R, may be connected to the machine, the upright portion thereof passing along over the last row planted, and is so adjusted as to mark the ground the distance required between the rows from the furrow-shovel next to it.

The width the hills in the row are to be made apart is governed and regulated by the size of the driving-wheel and the position in which the cam-blocks are placed.

When it is desired to make a corn-plow of the machine, the two back or covering shovels are moved forward and attached to the axle and set far enough on the inside of the furrow-

ing-shovels, so that the added shovels, in connection therewith, may pass on opposite sides of the corn-rows.

It is especially desirable that the cam-blocks on the driving-wheels should be adjustable, so as to change their position and action on the feed-slide to adapt the machine to the width the hills in the row are to be made apart. To accomplish this, any suitable means may be employed—such as clamps, set-screws, or bolts—and, if preferred, solid truck-wheels may be used in place of the spoke-wheels, as shown. The spring *m* may be connected to the seed-box by slot and set-screw, so that the point of attachment to its lower end may be lengthened or shortened to regulate the tension thereof, and its consequent action on the slide.

Having now fully described my invention, what I claim as new, and desire to secure by Letters Patent, is—

1. A frame carrying shovels, with means for elevating them, a guide connected to the frame, and seed-boxes connected to the axle by metal braces, in combination with a feed-

slide operated by cam-blocks on one of the drive-wheels, and flexible discharge-tubes for the seed, said tubes being rigidly secured to the slide and to the standards carrying the furrow-shovels, substantially as and for the purpose described.

2. A frame carrying shovels, with means for raising and lowering them, and seed-boxes supported over the axle of the machine by bracket, in combination with a seed-slide, and cam-blocks adjustably connected to one of the drive-wheels, and a spring connected to the end of one of the seed-boxes for acting on the slide, and flexible tubes for the discharge of the seed connected to the slide and moving with it and also to the standards of the furrow-shovels, substantially as and for the purpose set forth.

In testimony that I claim the above I have hereunto subscribed my name in the presence of two witnesses.

JOSEPH BOLLINGER.
